Primary Examiner — Katrina A Betton(74) *Attorney, Agent, or Firm* — Parsons Behle & Latimer(57) **CLAIM**

We claim the ornamental design for an aircraft suite window bay, as shown and described.

DESCRIPTION

FIG. 1 is a perspective view of an aircraft suite window bay showing the ornamental design as disclosed herein.

FIG. 2 is another perspective view of an aircraft suite window bay showing the ornamental design as disclosed herein; and,

FIG. 3 is side view of an aircraft suite window bay showing a closed window shade for the ornamental design as disclosed herein.

The elements shown in broken lines are included for the purpose of illustrating the environment for the ornamental design and form no part of the claimed design.
